UNITED STATES PATENT OFFICE

CHARLES F. YOCUM, OF FINDLAY, OHIO, ASSIGNOR TO THE BUCKEYE TRACTION DITCHER COMPANY, OF FINDLAY, OHIO, A CORPORATION OF OHIO

EXCAVATOR BUCKET

Application filed September 19, 1930. Serial No. 482,996.

This invention relates to excavator buckets of the open bottom type commonly used in connection with trench digging machines and having a plurality of laterally spaced fingers projecting inwardly and rearwardly from the rear edge thereof to assist in retaining a load in the bucket while moving from digging to dumping position.

In the use of buckets of this character, the rear fingers thereof, which have heretofore been rigidly attached at their inner ends to the buckets, are subjected to very hard usage, particularly when operated in stony soil, and are repeatedly bent and frequently broken off by the forcing of stones and other hard matter therebetween during the digging and cleaning operations.

The object of the invention is to attach the rear fingers to a bucket in such manner that they are permitted to have limited relative transverse movements as stones or the like are forced therebetween, the permanent bending of the fingers out of effective shape and the breaking of the same being thereby avoided, and the expense incident to correcting such bending or breaking eliminated.

Other objects and advantages of the invention will be apparent from the following detailed description, and while the invention is capable of different modifications, one embodiment thereof is illustrated in the accompanying drawings, in which,—

Figure 1 is a fragmentary side elevation of an excavator wheel with a bucket embodying the invention attached thereto and with a part broken away; Fig. 2 is a cross-section of a rim portion of the wheel looking toward the forward end of a bucket attached thereto; Figs. 3 and 4 are detail views of the finger attaching means for the buckets, and Fig. 4, in addition, shows the casting to which the fingers are secured as being separate from the steel plate forming the bucket body.

Referring to the drawings, 1, 1 designate the two transversely spaced annular rim members customarily employed in excavator wheel construction, and 2 a bucket spanning the space between the rim members and rigidly attached thereto at its ends, as well understood in the art. The forward or cutting

edge of the bucket may have the customary teeth 3 and the rear edge has the rod-like fingers 4 projecting inward and rearwardly therefrom in transversely spaced relation to serve as the means at the rear end of the bucket for retaining a load therein during a portion of the movement of the excavating wheel, as well understood in the art. It will be understood that a plurality of these buckets are provided in equidistantly spaced relation around the wheel.

In carrying out the feature of the invention, each finger or rod 4, which is preferably of spring steel, has its inner end mounted loosely in a socket 5 provided in the rear edge portion of the bucket and is secured thereto by a single rivet or like member 6. The sockets 4 are disposed lengthwise of the buckets and are open at the rear ends for the insertion of the fingers. The looseness in fit between the fingers and socket is preferably only between the side edges thereof so that the fingers are permitted to have limited pivotal movements transverse to the bucket about the rivets 6 as axes and are held substantially rigid against movement in a plane lengthwise of the finger and parallel to the respective rivet axes.

In practice, especially when operating in stony soil, the fingers are preferably sufficiently loose to have transverse movements at their ends of about one-half inch in either direction from normal, thus enabling two adjoining fingers to separate approximately one inch at their ends. This enables stones which are considerably larger than the normal space between the fingers to spread the fingers apart and pass therebetween without breaking the fingers or so permanently bending the same as to lessen their efficiency and necessitate replacement or straightening. The customary cleaner fingers, not shown, pass between the fingers 4 and tend to normally maintain them in parallel relation.

In practice, the buckets 2 are usually made from steel plate and inasmuch as it would be difficult and expensive to form such plate with the sockets 5 for receiving the fingers 4, these sockets are preferably formed in a cast steel member 7 that is set in an incut 8 in

the rear edge of the plate material and integrally secured at its edge to the edge wall of such incut by welding, as indicated at 9.

It is apparent that I have provided a simple and efficient form of attaching means for the rear fingers of excavator buckets which will permit such fingers to have relative transverse separating movements to enable stones and other hard articles, which are of greater size than the normal spaces between the fingers, to pass therebetween without imparting a permanent bend to the fingers or breaking the same, both of which very frequently occur where rigid fingers are used. This not only continues the efficient working condition of the buckets, but saves the expense and labor incident to replacing broken and permanently bent fingers and also saves the time incident to replacing the same.

20 I wish it understood that the invention is not limited to any specific construction, arrangement or form of the parts, as it is capable of various modifications without departing from the spirit of the claims.

25 Having thus described my invention, what I claim as new and desire to secure by United States Letters Patent is:

1. An excavator bucket of the class described, having fingers projecting rearwardly and inwardly from its rear edge and connected thereto for limited relative transverse movements.
2. A bucket of the class described, having fingers projecting inwardly and rearwardly from its rear edge and pivoted thereto for limited relative movements transverse to the bucket.
3. A bucket of the class described, having lengthwise extending sockets in its rear edge, and fingers projecting from the rear edge of the buckets with their inner ends anchored in said sockets for limited relative movements transverse to the bucket.
4. A bucket of the class described, having lengthwise extending sockets in its rear edge portion, and fingers projecting from the rear edge of the bucket and having their inner ends pivotally anchored in the sockets and of less width than the sockets to permit the fingers to have limited relative pivotal movements transverse to the bucket.
5. In an excavator wheel, a bucket, fingers projecting inwardly and rearwardly from the rear edge of the bucket and pivotally anchored to the bucket for limited relative movements lengthwise of the wheel axis.
6. An excavator bucket of the class described having its major body portion of steel plate with an incut at its rear edge, a steel casting fitting said incut and welded to the steel plate to form a continuation thereof and having rearwardly opening sockets therein, rod-like fingers projecting inwardly and rearwardly from the rear edge of the bucket and having their inner ends projected into said

sockets for limited movements therein transverse to the buckets, and means pivotally anchoring the fingers in the respective sockets.

In testimony whereof I have hereunto signed my name to this specification.

CHARLES F. YOCUM.
